UNITED STATES PATENT OFFICE.

CHARLES B. LORD, OF LONG ISLAND CITY, NEW YORK.

FUEL-SAVING DEVICE FOR LOCOMOTIVES.

SPECIFICATION forming part of Letters Patent No. 595,821, dated December 14, 1897.

Application filed January 12, 1897. Serial No. 619,011. (No model.)

To all whom it may concern:

Be it known that I, CHARLES B. LORD, residing at Astoria Station, Long Island City, in the county of Queens and State of New York, have invented a new and useful Fuel-Saving Device for Locomotives, of which the following is a specification.

This invention relates generally to locomotives, and more particularly to an attachment whereby an even draft is maintained, economizing greatly in the use of fuel.

Heretofore in locomotives as generally constructed the draft has been created by the exhaust-nozzle which leads from the steam-cylinders. This plan, however, has been very wasteful to the fuel, inasmuch as the blast from the exhaust-nozzle draws the fuel from the fire-box and ejects the same through the smoke-stack before it has been subjected to the proper combustion, and it is therefore impossible to obtain all of the heat from any given quantity of fuel. Furthermore, the use of wire-netting, petticoat-pipes, &c., has been necessary in order to prevent the exhaust-nozzle ejecting sparks from the smoke-stack, and all of these devices, however, seem to more or less interfere with the draft.

The object, therefore, of my invention is to avoid all of these objections and create a draft by a blower only, which is operated by the surplus steam from the boiler-head; and another object of the invention is to carry the exhaust-steam continuously from the saddle to the top of stack in order to reduce the noise from the exhaust and the back pressure upon the pistons to a minimum.

With these objects in view my invention consists, essentially, in continuing the exhaust-pipe to the end of the smoke-stack upon either the inside or the outside and arranging a blower-nozzle directly below the center of the stack, whereby an even and steady draft is obtained by a moderate use of the blower while using steam through the cylinders.

The invention consists also in providing a detachable blower which can be quickly and easily attached or detached as desired.

The invention consists also in providing an expansion-chamber directly above the saddle,

whereby the back pressure upon the pistons is reduced to a minimum.

The invention consists also in certain details of construction and novelties of combination, all of which will be fully described hereinafter and pointed out in the claims.

In the drawings forming a part of this specification, Figure 1 is a view showing the practical application of my invention. Fig. 2 is a detail view showing the manner of arranging the blower-pipe in connection with the exhaust-pipe, said exhaust-pipe being arranged at one side of the stack and provided with an expansion-chamber. Fig. 3 is a detail view showing the manner of arranging the blower in connection with the exhaust-pipe, arranged centrally with the stack and provided with an expansion-chamber. Fig. 4 is a detail sectional view showing the manner of connecting the blower-nozzle to the steam-pipe. Fig. 5 is a detail perspective view of the blower. Fig. 6 is a detail view showing a modified form of exhaust-pipe and stack. Fig. 7 is a transverse section on the line 7 7 of Fig. 6.

In carrying out my invention I employ a blower A, which consists, essentially, of a pipe bent in the form of a triangle and provided with a series of jet-nozzles A' upon the upper side thereof. The lower portion of the blower is screw-threaded, as shown at B, and has a collar C fastened thereon, said collar having notches or recesses D produced therein at definite points. The pipe E, leading from the boiler-head or steam-dome, is also threaded at its upper end to receive the sleeve F, the upper interior portion of the said sleeve being smooth in order to permit the collar C slipping therein, and attached to the exterior of the sleeve F are the springs G, constructed with inwardly-projecting locking-pins H, which pass through openings I in the sleeve F and engage the recesses or notches D, produced in the collar C, and thereby securely connect the blower with the supply-pipe. In order to effect such connection, it is only necessary to insert the lower end of the blower, provided with a collar C, and in order to detach the blower it is only necessary to press the springs outwardly, which operation withdraws the locking-pin H, and the blower can then be

lifted from the sleeve F. It will of course be understood that the collar C can be dispensed with, if desired, and the lower portion of the blower provided with notches or recesses to receive the locking-pins H. It will also be understood that the end of the pipe E can also be provided with the springs G and thereby avoid the necessity for the sleeve F.

K indicates the exhaust-pipe, which leads from the cylinders and extends entirely through the smoke box or chamber and through the smoke-stack to the top thereof, said exhaust-pipe being arranged at one side of the stack, as shown at Fig. 2, or center thereof, as shown in Fig. 3. In either case I prefer to construct the exhaust-pipe with an expansion-chamber L, which permits the exhaust-steam to expand as it escapes and thereby reduce the back pressure upon the pistons to a minimum.

The pipe E is secured or held in place by means of a bracket M, which is attached to the exhaust-pipe K, as most clearly shown in Figs. 1, 2, and 3.

It will be noted that the blower is arranged directly beneath the center of the smoke-stack in order to create the proper draft, and in case the exhaust-pipe is arranged centrally of the smoke-stack, as shown in Fig. 3, the member or nozzle portion of the blower is curved to embrace the said pipe, as clearly shown in Fig. 3. The essential features, however, remain the same in all of the constructions.

The operation of my device is clear to every one skilled in the art to which it pertains, as it will be seen that a uniform draft will be maintained at all times by the use of the blower supplied directly from the boiler-head, and it will also be noted that the noise of exhaust and the back pressure upon the pistons will be reduced to a minimum. Fur-

thermore, the wire-netting and petticoat-pipes are entirely dispensed with, as well as spark-arresting devices of all constructions.

Having thus described my invention, what I claim as new, and desire to secure by Letters Patent, is—

1. In a locomotive, an exhaust-pipe extending from the saddle through the smoke-stack and to the top of the stack and enlarged, within the smoke-box, to form an expansion-chamber, in combination with a live-steam blower partly around the exhaust-pipe and supported from said exhaust-pipe, all substantially as set forth.

2. In a locomotive, in combination, the boiler-head, a draft-nozzle located below the stack, a pipe leading from the boiler to the nozzle, and a spring-operated detachable connection between the pipe and nozzle, all substantially as set forth.

3. In a locomotive, the combination with the pipe leading from the boiler-head, having holes through its sides near the end, the blower-pipe having holes or notches registering with the holes on the steam-pipe when they are jointed together, and the springs secured to the steam-pipe and carrying pins or tongues to pass through the holes in the sides of the steam-pipe and enter the holes in the blower-pipe, all substantially as set forth.

4. The combination with the triangular-shaped blower provided with a series of jet-nozzles, the notched or recessed collar carried by the said blower, the pipe and sleeve and spring carrying the locking tongues or pins, all arranged and adapted to operate, substantially as shown and described.

CHARLES B. LORD.
